QUILLING MACHINE

George Adsit, deceased, late of East Paterson,
N. J., by Blanche W. Adsit, executrix, East
Paterson, N. J.

Application October 16, 1931, Serial No. 569,202

14 Claims. (Cl. 242—27)

This invention relates to quilling machines and its object is to improve the mechanism of such machines whereby to render them more reliable and efficient in operation and capable of being operated with more facility and less skill on the part of the attendant and also capable of being adapted by simply effected changes for the winding of either quills or the like cores having enlargements at their butts or cops of the like lacking such enlargements.

The invention consists in novel means for establishing and disestablishing a driving connection between the driving means of the machine and the mechanism to be driven thereby; in novel means for maintaining such connection automatically when once established, the same being however adapted to cause release when required by the attendant; in a novel mounting of one of the two means formed by the spindle and thread-guiding means so that one is movable toward and from the other; and in novel means whereby the machine is adapted for the winding of cops.

In the drawings,

Fig. 1 is a plan of one of the winding units, complete, with the frame in section;

Fig. 2 is a side elevation of such unit, with the frame in section;

Fig. 3 is a vertical front-to-rear section taken in a plane between the spindle and thread-guiding means of such unit;

Fig. 4 is a front elevation, with parts in section;

Fig. 5 is a section on line 5—5, Fig. 3;

Fig. 6 is a longitudinal section of the clutch;

Fig. 7 is a section on line 5—5, Fig. 3, but looking rearward;

Fig. 8 is a section on line 8—8, Fig. 7;

Figs. 9, 10 and 11 are sections on lines 9—9, 10—10 and 11—11, respectively, Fig. 1;

Fig. 12 is a side elevation of a winding unit constructed for the winding of so-called cops or the like;

Figs. 13 and 14 are sections on lines 13—13 and 14—14, respectively, Fig. 12, and

Fig. 15 shows a cop.

1 is the frame, 2 one of a horizontal row of bearings therein for pulleys or drivers 3 driven by a belt 4 and 5 a horizontal rock-shaft extending at right angles to the bearings 2, so much bearing according to the known construction.

Each spindle 6 (which may have the spindle proper 6a screwed or otherwise removably secured thereto) is coaxial with one of the pulleys and 55 is journaled at its forward portion in the frame

and capable of reciprocation longitudinally. It is adapted to be disconnectionally connected with its pulley by a clutch described thus: The pulley has a cup-extension 3a which forms itself one member of the clutch. The other clutch member comprises a sleeve structure itself comprising outer and inner sleeve portions 7 and 8 forming between them a spring cavity 9; a split conical spring ring 10 inset in a circumferential groove 11 in the sleeve structure and adapted when the latter is forced telescopically into the pulley-cup 3a to establish a friction grip between them; a thimble 12 to abut the pulley at this time; and a spring 13 housed in the cavity between the thimble and the forward or closed end of the cavity, 60 the thimble being preferably splined to the sleeve structure at 14. The sleeve structure may have a bearing collar 15 for the spindle, which at 16 has a collar fixed thereto and formed with keys 17 to engage in a spline 18 of the sleeves of the 65 sleeve structure. Thus, the pulley being in rotation, the thrustwise-movable clutch member may be moved one way or the other to establish or disestablish a rotary driving connection between the pulley and spindle, such movement being independent of the spindle. The opening movement of the movable clutch member may be limited by an arm 44 hereinafter referred to (Figs. 1 and 10). 70

The movable clutch member is shifted back or forth from a control rod 19 or controller having a fork 19a engaging between collars 20 and 20a on said member (the former of which may be of yielding material) and slideable in the frame and bearing 2 and projecting at the front, being normally urged forward by a spring 21 between the fork and bearing and being adapted to be moved forward or back by a hand-lever 22 fulcrumed in the frame and having fingers 22a between which lies a stud 19b on the rod. The rod is held releasably back, holding the clutch closed, by 75 the following means (Figs. 5 and 9): Affixed to it is a projection or arm 23 which by gravity, assisted by a spring-pressed arm 24 pivoted thereon and bearing against a rod 40 (to be described) is held normally depressed (the rod 19 having some 80 slight rocking motion for the purpose). The end of the projection occupies the crotch of an angle-lever detent 25 movable in a vertical front-to-rear plane to limits afforded by its supporting bracket 26 in which one or the other arm of the 85 detent is up. When the rod 19 is moved forward or backward the projection shifts this detent one way or the other. When it is moved back, to establish the clutch, arm 25a of the detent is so 90 fashioned that the projection (urged downward as 95 100 105 110

described) forces the detent to the dotted line shown in Fig. 9, or where the fulcrum of the detent is in the path of return movement of the projection with the controller (rod 40 being cut away at the top at 40a, Figs. 2 and 7, to permit the projection to assume this position) and the lever bears against a stop formed by the bracket 26; in this position of the parts, therefore, the rod will be locked back, maintaining the clutch closed. The bracket is split at 26a, the portion above the split forming said stop, which is adjustable up and down by providing an adjusting screw 27 set in one and bearing against the other portion of the bracket as thus split and a clamping screw 28 connecting them. In this example the controller may be released by sufficient sudden downward pressure on the lever 22, taken with some rocking of the controller in its bearings, to jar the projection upward so that it then rocks 20 the detent to permit return of the controller.

For reciprocation of the spindles rock shaft 5 has cranks 29 connected with the spindles thus (Figs. 7 and 8): Each such crank has pivoted thereto on an axis parallel with the rock shaft 25 a lever 30 fulcrumed in an arm 31 pivoted to the frame, wherefore as the crank oscillates this lever will be oscillated thereby around such fulcrum. The spindle revolves in a bracket 32 kept from rotating by having a fork receiving rod 19 (Fig. 7) 30 and confined to the spindle between two collars 33 thereon. The lever 30 and this bracket have upright slots 34 facing each other (Figs. 1 and 9) and they receive rollers 35 on a link 36 pivotally connected with a lever 37 (Fig. 2) fulcrumed in 35 the frame and itself connected by a link 38 with an arm 39 fixed on the rod 19. When the rollers 35 coincide with the fulcrum of lever 30 (see Fig. 7) the crank 29 will obviously impart no motion to the spindle; but when rod 19 is repressed to close 40 the spindle-rotating clutch and the link consequently elevates the rollers in slots 34 reciprocation will be imparted to the spindle. Thus to start or stop a spindle (as to both rotation or reciprocation) requires simply movement of rod 19 45 backward or forward.

A rod 40 is journaled to oscillate in frame 1 and it has affixed thereto bearing brackets 41 and 42, forming therewith a carrier which is urged clockwise in Fig. 4 by a spring 43 (Fig. 2) coiled about 50 the rod and engaged with frame 1 and an arm 44 secured on the rod, this movement of said carrier being limited by contact of an adjusting screw 45 in bracket 41 with a stop 46 on the frame (Figs. 1 and 4). In the brackets of said carrier is arranged the thread-guiding means comprising the thread-guide rod 47, having the thread-guide 48, and the revoluble threaded thread-guide-advancing rod 49 having the friction wheel 50 to bear on the package being formed on the spindle, the two 55 rods being connected to move together longitudinally by fork 51 on the rod 47 engaged between collars 52 on the rod 49; to permit the rods to rock with the carrier they project through slots 47a—49a in the front of the frame 1. A collar 53 adjustable on rod 49 limits the forward motion of the two rods 47—49, interconnected at 51, and their rearward motion is limited by a stop device 54 adjustable on rod 40 and engageable by collar 52. In the bracket 42 is a block or nut 55 having 60 teeth or threads 55a which are held engaged with the threads of rod 49 by a spring 56, these teeth having inclined forward faces (Fig. 2) and square-cut rear faces whereby when the winding 70 is going on the square-cut faces will properly contact with the thread of rod 49 to advance the lat-

ter but the operator may push back the rods 49—47, the inclined faces of the nut then sliding over the thread of rod 49. A cylindrical housing 57 encloses the forwardly projecting part of the spindle and the quill *a*, projecting from the front face of the frame and protecting the package being wound thereon from lubricant thrown off by the other parts; its upper portion forms a hinged cover which may be raised when doffing.

The operation may be briefly stated as follows: The pulley 3 and rock-shaft 5 are constantly driven. Having placed a quill *a* on the spindle with the thread-guiding means in its back position and attached the thread to be wound to the quill the lever 22 is operated to close the clutch and thus start the spindle rotating and shift link 36 to the position where crank 29 will be effective, as described, to reciprocate the spindle. Each time the friction wheel is engaged by the conical portion of the quill (or later the resulting cone of the windings) as the spindle reciprocates rod 49 is rotated somewhat and by its engagement with nut 55 causes the thread-guiding means to advance. The carrier of said means yields rotatively around the axis of rod 40 on each impact 100 of the windings with the friction wheel, to permit the latter to run up the cone. When the winding of any unit is completed the collar 53 encounters the arm 25b of detent 25, which trips the detent so that rod 19 is free to advance to 105 disestablish the clutch and return rollers 35 to the position coaxial with the fulcrum of lever 30, or neutral, wherefore the motion (both rotary and reciprocatory) of the spindle ceases.

In respect to the means for causing traverse of the yarn, it is apparent that it is not material which of the two elements constituted by the spindle and a part such as rod 40 is reciprocated, though in this example it is the spindle; nor is it material to which of the two elements the lever is pivoted; nor that the actuator (29) move back and forth by oscillating rather than by some other movement generally lengthwise of the axis of said spindle. The use of a lever, as 30, in this connection makes it impossible for the attendant to establish the reciprocated means reciprocating its fall stroke suddenly, or without gradually increasing the length of the stroke, so that undue strain on the thread being wound is at this time also impossible.

One important feature of the invention is that the thread-guiding means is supported by a carrier rockable in the supporting structure around an axis substantially parallel with that of the spindle. Heretofore (see Adsit Patent No. 1,178,045) movability of the thread-guiding means toward and from the spindle was obtained by supporting it so as to be oscillatory around an axis transverse to it and adjacent its rear end, which made its action uncertain and irregular and incapable of producing the nicely formed packages possible by the present construction.

When a quill or the like having a pronounced cone or enlargement at its butt is used such cone affords an abutment for impact of the friction wheel with the cone at the start of the winding. But when a paper cop or the like, as *b*, Fig. 15, is used which lacks such pronounced enlargement it is necessary, as is known, to build up a synthetic, as it were, enlargement of windings on the cop, and this, which is to form the heel of the package, should have a nicely defined conical rear face. In Figs. 12 to 14 mechanism for performing the winding of a cop is shown.

It will be understood that in this example the spindle and the means for effecting and controlling its two motions (rotary and reciprocatory) are the same as above described; likewise 5 is the thread-guiding means comprising the mentioned carrier and thread-guide and thread-guide-advancing rods, excepting that in this form a spring 58 urges said means laterally away from the spindle, or anti-clockwise as viewed from 10 the front. Rod 40 of said means has affixed thereto a bracket 59 in which is fulcrumed between its ends an upright lever 60 confined to move in a plane parallel with the rod. This lever is normally urged by a spring 61 clockwise in Fig. 15 12 and its lower end has a roller 62 bearing against an oblique surface 63a of a fixed guide 63, its upper end having a stud 64 in the path of the collar 20 52 already mentioned. Surface 63a is pitched to the angle which it is desired the butt surface of the wound mass should present. 64a is a stud on the lever which may abut an adjustable stop 65 on rod 40. The carrier's proximity to the spindle therefore depends on the point in surface 63a at which the lever 60 (to wit, its roller) engages 25 said surface.

When the control rod is repressed to start the winding operation collar 52 tilts the lever 60 anti-clockwise and as its roller travels along surface 63a the thread guiding means is urged, against the 30 tension of spring 58, toward the cop 'b' on the spindle. When the spindle is now driven and as soon as some windings form on the cop the thread-guide-advancing rod (by contact of the friction wheel with these windings incident to the reciprocation of the cop with the spindle) undergoes 35 intermittent rotation. This advances the thread-guiding means, with consequent clockwise movement of the lever under tension of its spring so that it runs, as it were, down the incline 63a and so allows the thread-guiding means to recede from the cop. This process goes on gradually, the windings forming in stepped layers on the cop which develop a rearward taper having more or less the same angularity as surface 63a. In 40 this way the butt or heel of the package is formed. This action continues as long as the lever's motion under tension of its spring 61 is not checked. It may be checked at any point (thus to determine the diameter of the cone of the package heel or 45 butt and hence of the cylindrical part of the package) according to the position of stop 65. Upon the rearward cone of the package 'c' being developed in this way the operation to finish the package is the same as that heretofore described, or as in winding a quill. When the operation of 50 winding is completed and a fresh cop is to be wound the attendant represses the thread-guiding means to reset lever 60 in the position where it engages the outer end portion of surface 63a and said means proximates the cop.

To change the machine to adapt it to winding cops instead of quills requires only to remove the parts 43 and 54 and add the parts 58 to 65.

While the lever and surface 63a are utilized in the present instance in actually controlling motion of one of two means (spindle and thread-guiding means) directly concerned in the winding transversely of the winding axis and during the winding and also on resetting for starting the winding anew it will be seen that essentially these instrumentalities together determine the distance apart which said means may assume according to the position the lever is turned around its fulcrum.

Having thus fully described the invention what is claimed is:

1. In a mechanism for forming a wound thread package, the combination of supporting structure, a rotary driver journaled therein, a rotary and reciprocatory spindle axially aligned with the driver, a clutch member penetrated by and splined to the spindle, said members having telescoping portions and one being movable relatively to the other lengthwise of the spindle, and an elastic device confined by one such portion against appreciable movement relatively thereto lengthwise of the spindle and arranged on telescoping one of said portions into the other to be received by the latter and frictionally engaged both of them. 80

2. In a mechanism for forming a wound thread package, the combination of supporting structure, a rotary driver journaled therein, a rotary and reciprocatory spindle axially aligned with the driver, a clutch member penetrated by and splined to the spindle, said members having telescoping portions and one being movable relatively to the other lengthwise of the spindle, an elastic device confined by one such portion against appreciable movement relatively thereto lengthwise of the spindle and arranged on telescoping one of said portions into the other to be received by the latter and frictionally engage both of them and elastic means normally holding the movable member in the position where said device is withdrawn from the member adapted to receive the same. 95

3. A traverse winding mechanism comprising, with supporting structure and an element to be reciprocated to cause traverse of the windings, an actuator element, means to reciprocate the actuator element constantly to predetermined limits, an arm pivoted in said structure, a lever connected to one element and fulcrumed on said arm to move in a plane extending lengthwise of the traverse, 110 and a coupling connected with the lever to shift toward and from its fulcrum and with the other element, whereby to transmit reciprocation variable in extent from the actuator to the element to be reciprocated. 115

4. A traverse winding mechanism comprising, with supporting structure and an element to be reciprocated to cause traverse of the windings, an actuator element oscillatory on an axis crossing the path of reciprocation of the first element, a lever pivoted to the actuator element, a coupling connected with the lever to shift toward and from its fulcrum and with the first element, and a member in which the lever is fulcrumed at a point removed from its pivoted connection with the actuator element and also eccentric of said axis, said member being carried by said structure and free to shift therein toward and from said axis. 130

5. In a mechanism for forming a wound thread package, the combination of supporting structure winding means, means to drive the winding means, a clutch disconnectively connecting the first two means, a clutch controller movable back and forth and having a lateral projection, a two-armed lever receiving said projection between its arms and fulcrumed in said structure on an axis crossing the path of movement of the controller, said controller being normally urged transversely of its said back and forth movement and thereby holding said projection pressing against the lever and on movement of the controller back or forth being adapted by engagement with one arm or the other to shift the lever, and said structure having a stop for the lever when moved in one direction by the controller so positioned that the fulcrum of the lever 140 145 150

- is then substantially in the path of return movement of the projection with the controller.
6. In a mechanism for forming a wound thread package, the combination of supporting structure, 5 winding means, means to drive the winding means, a clutch disconnectively connecting the first two means, a horizontally and longitudinally movable clutch controller rod movable back and forth and having a projection, a two-armed lever fulcrumed 10 in said structure beside and on an axis crossing the rod and under said projection and receiving the latter between its arms, said controller being normally urged transversely of its said back and forth movement and thereby holding said projection pressing downward on the lever and on movement of the rod back or forth being adapted by engagement with one arm or the other to shift the lever, and said structure having a stop for the lever when moved in one direction by the rod so 15 positioned that the fulcrum of the lever is then substantially in the path of return movement of the projection with said rod.
7. In a mechanism for forming wound thread packages, the combination of supporting structure, 20 a rotary device journaled therein on which to wind the thread, a carrier device rockable in said structure around a fixed axis substantially parallel with that of the rotary device, thread-guiding means in the carrier device including a thread- 25 guide rod and a thread-guide-advancing rod coupled to move together lengthwise of, and the latter being revoluble around an axis substantially parallel with, said axes, and engageable and adapted to be rotated by the windings and having a screw-thread, said rods being confined by the carrier to 30 approximate parallelism with each other and means engaging said screw thread to advance guiding means when the advancing rod is rotated.
8. In a mechanism for forming wound thread packages, the combination of supporting structure, 35 a rotary device journaled therein on which to wind the thread, a carrier device comprising an oscillatory rod confined in said structure to substantially parallel relation to the axis of said 40 rotary device and brackets mounted on the rod, thread-guiding means including a thread-guide and a thread-guide-advancing rod coupled to move together in said brackets lengthwise of, and the latter being revoluble around an axis sub- 45 stantially parallel with, said axes and being engageable and adapted to be rotated by the windings and having a screw-thread, and means in the carrier engaging said screw-thread to advance said guiding means when the advancing 50 rod is rotated.
9. In a mechanism for forming a wound thread package, the combination of supporting structure, 55 rotary means on which to wind the thread, thread-guiding means, a carrier structure shift- 60 able back and forth in said supporting structure transversely of the axis of said rotary means, one of said means being mounted in the supporting and the other in the carrier structure and one of said structures having a surface oblique to said axis, and a lever arranged to bear against said 65 surface of the structure having such surface, and confined to move pivotally on the other structure in a plane angularly related to said surface.
10. In a mechanism for forming a wound thread 70 package, the combination of supporting structure, rotary means on which to wind the thread, thread- 75 guiding means, a carrier structure shiftable back and forth in said supporting structure around an axis substantially parallel with the axis of said rotary means, one of said means being mounted in the supporting and the other in the carrier structure and one of said structures having a surface oblique to said axes, and a lever arranged to bear against said surface of the structure having such surface, and confined to move pivotally on the other structure in a plane angularly related to said surface.
11. In a mechanism for forming a wound thread package, the combination of supporting structure, 80 rotary means on which to wind the thread, thread-guiding means, a carrier structure shift- 85 able back and forth in said supporting structure and normally urged in one direction transversely of the axis of said rotary means, one of said means being mounted in the supporting and the other in the carrier structure and one of said structures having a surface oblique to said axis, and a lever arranged to bear against said surface of the structure having such surface and confined to move pivotally on the other structure in a plane angularly related to said surface.
12. In a mechanism for forming a wound thread package, the combination of supporting structure, 90 rotary means on which to wind the thread, thread-guiding means, a carrier structure shift- 95 able in said supporting structure transversely of the axis of said rotary means, one of said means being mounted in the supporting and the other in the carrier structure and one of said structures having a slot oblique to said axis, and a lever engaged in the slot of the structure having such slot and confined to move pivotally on the other structure in a plane angularly related to the slot.
13. In a mechanism for forming a wound thread package, the combination of supporting structure, 100 rotary means on which to wind the thread, thread-guiding means, a carrier structure shift- 105 able back and forth in said supporting structure and normally urged in one direction transversely of said axis, one of said means being mounted in the supporting and the other in the carrier structure and the latter means being advanceable in 110 the carrier structure relatively to the other means and lengthwise of said axis to cause axial progress of the winding and also movable reversely, and said supporting structure having a surface oblique to said axis, and a lever arranged to bear against 115 said surface and confined to move pivotally on the carrier structure in a plane angularly related to said axis, said lever being normally urged to move pivotally in one direction but being movable by the advanceable means when the latter 120 is moved reversely.
14. In combination, supporting structure, an oscillatory element journaled therein and normally urged in one direction lengthwise of its axis and having a lateral projection, and means to 125 hold said element, when moved in the opposite direction, against movement in the first direction comprising a bell-crank lever having its crotch facing in the second direction and receiving in said crotch the contact of said projection, said 130 lever when so positioned being opposed by said structure against movement in one direction but being free to be moved in the other direction by the projection when said element is rocked.
